CLAIM

The ornamental design for a dermatome or the like, as shown and described.

DESCRIPTION

FIG. 1 is a perspective view of a dermatome or the like showing our new design;

FIG. 2 is a top plan view thereof;

FIG. 3 is a left side elevational view thereof with the right side being a mirror image except for the adjustment lever and scale marks and with the throttle lever arm in a raised position;

FIG. 4 is a bottom plan view thereof;

FIG. 5 is a front elevational view thereof; and

FIG. 6 is a rear elevational view thereof.

FIG. 1**FIG. 2**

FIG. 3**FIG. 4****FIG. 5****FIG. 6**
